UNITED STATES PATENT OFFICE.

JAMES M. WALSH, OF MILWAUKEE, WISCONSIN, ASSIGNOR TO WALSH HARNESS COMPANY, OF MILWAUKEE, WISCONSIN, A CORPORATION OF WISCONSIN.

BRIDLE.

1,280,910.

Specification of Letters Patent.

Patented Oct. 8, 1918.

Application filed March 10, 1915, Serial No. 13,307. Renewed February 19, 1918. Serial No. 218,181.

To all whom it may concern:

Be it known that I, JAMES M. WALSH, a citizen of the United States, residing at Milwaukee, in the county of Milwaukee and State of Wisconsin, have invented certain new and useful Improvements in Bridles, of which the following is a specification, reference being had to the accompanying drawing, forming a part thereof.

10 The main objects of this invention are to facilitate adjustment to horses of different sizes or having heads and necks of different sizes and forms; to reduce the quantity of leather required for a bridle; to eliminate billets or perforated strap ends for buckles, which not only require extra leather for adjustment, but also weaken the straps connected thereby; to avoid rubbing, wear and weakening of the leather where straps are 15 attached to metal fittings, and thus prolong the life of the bridle; to prevent accidental detachment of the parts of the bridle and thus insure safety in its use; and generally to simplify and improve the construction of 20 bridles.

It consists in the construction, arrangement and combination of parts as herein-after particularly described and pointed out in the claims.

30 In the accompanying drawing like characters designate the same parts in the several figures.

Figure 1 is a perspective view of a bridle embodying the invention, parts of the front blind or winker and of the front cheek plate of the bit being broken away; Fig. 2 is an enlarged vertical section of the throat latch buckle and part of the gag strap; Fig. 3 is a front elevation on a smaller scale 35 of the adjustable throat latch fastening and associated gag runner; Fig. 4 is an enlarged sectional detail of the adjustable connection between the bit and cheek strap on one side of the bridle; Fig. 5 is a sectional detail 40 of the adjustable throat latch fastening and associated gag runner; Fig. 6 is a detail view on a larger scale of the lower end of one of the chains connecting the cheek straps 45 and view showing one of the metal rings or fittings for connecting the nose and cheek straps of the bridle; Fig. 7 is a detail view on a larger scale of the lower end of one of the chains connecting the cheek straps 50 and the bit; Fig. 7 is a horizontal section on the line 7—7, Fig. 4, of one of the cheek plates or pieces of the bit; and Fig. 8 is a

view similar to Fig. 3, of a modified arrangement of the adjustable throat latch fastening and associated parts.

55

The bridle comprises cheek bands or straps *a*, formed integrally of leather, with blinds or winkers *b*, a crown band or strap *c* inseparably connected at the ends by metal rings or fittings *d* with the upper ends of the cheek bands or straps and with the front or brow band or strap *e*, a nose band or strap *f*, inseparably connected at the ends by metal rings or fittings *g* with the lower ends of the cheek bands or straps, and a bit *h*, provided at the ends with cheek or mouth rings, plates or pieces *i*, which are adjustably connected by chains *j* with the rings *g*.

60

The blinds or winkers *b*, as shown in Fig. 1, are preferably formed integrally with the cheek bands or straps *a*, from a single thickness of leather and are reinforced and stiffened with the adjoining portions of said bands or straps, as shown in Fig. 1, by wires *k*, inserted through the edges of the leather between and parallel with its opposite faces. After the reinforcing wires have been thus inserted in the leather, the blinds are pressed between dies 70 into concavo-convex form as indicated by the shading in Fig. 1, the wires being sufficiently annealed to retain the form into which they are bent.

75

The upper links of the chains *j* are looped 80 around the lower cross bars of the rings *g* and are thus pivotally and inseparably connected with the lower ends of the cheek straps *a*. The cheek plates *i* are formed on the upper sides, as shown in Figs. 1 and 4, 85 with outwardly and downwardly bent hooks *l*, with which corresponding links of the chains *j* on opposite sides of the bridle are engaged, thereby adjustably connecting the bit with the cheek straps and providing for 90 lengthening and shortening the bridle for horses of different sizes or having heads of different lengths.

95

The hooks *l* are bifurcated, as shown in Fig. 1, and dogs *m* are pivoted therein to retain the links on the hooks in engagement therewith, as shown in Fig. 4. Below the hooks *l* the plates *i* are formed on the outer sides with guideways or keepers *n*, for confining the lower ends of the chains *j* and 100

105

preventing them from rattling and wearing. These guideways are formed at the sides, as shown in Figs. 4 and 7, with grooves *o*, which are open at their lower ends and closed 5 at their upper ends, and the lower links of the chains have their cross bars extended to form lateral projections *p*, which enter these grooves from the lower ends and by engagement with the closed upper ends thereof, 10 prevent accidental separation of the bit from the chains in case the chains are disengaged from the hooks *l*. The plates *i* are formed, as shown in Fig. 1, at the sides of the guideways *n* with a series of openings *q* 15 for adjustable attachment to the bit of the reins *r* and check *s*, which are provided at their ends with hooks *t* and *u*.

For the sake of appearance the openings *q* are symmetrically formed on both sides of 20 the guideways *n*, and the guideways are of reticulated construction corresponding with the links of the chains.

A strap or band *v*, designated the gag strap and made in a single piece or in two 25 sections stitched or otherwise fastened to the upper part of the crown strap or band *c*, obliquely thereto, is looped at its ends around and stitched or otherwise fastened to the cross bars of gag runners *w*. The 30 gag runners are provided with grooved pulleys *x*, over which round portions of the check *s* are guided, as shown in Figs. 1 and 3. One of the gag runners is formed at its lower end with an eye *y*, and the other with 35 a loop *z*. The throat latch 2, is provided at one end with a hook 3, for detachable engagement with the eye *y*, and at the other end with a buckle or fastening for adjustably connecting it with the gag strap *v* on 40 the opposite side of the bridle, as shown in Figs. 1 and 3. This buckle or fastening preferably consists, as shown in Figs. 1, 2 and 3, of a plate 4, formed on opposite sides with ears 5, between which the gag strap *v* 45 is guided, and a loop or ring 6 formed with a cross bar around which the end of the throat latch is looped and fastened, and with a sleeve 7 pivotally mounted on a cross pin between the ears 5. The sleeve 7 is 50 formed on the side toward the plate 4 approximately at right angles to the sides of the ring 6, with two studs 8, adapted to engage with any pair of two series of holes in the gag strap *v* when the ring 6 is turned 55 down against or parallel with said strap. The gag strap *v* or the perforated end thereof, is made enough wider than the throat latch 2, to provide the same cross section 60 exclusive of the buckle holes and give it the same strength as the throat latch. The end of the throat latch to which this adjustable fastening is attached may be placed inside of the gag strap *v*, as shown in Fig. 3, and as viewed from the front of the bridle, or the 65 arrangement reversed, as shown in Fig. 8,

and as viewed from the rear of the bridle, the throat latch passing outwardly through the gag runner frame between the pulley *x* and the cross bar above it to which the gag strap *v* is fastened. The latter arrangement is preferable, as it facilitates the adjustment of the throat latch when the bridle 70 is on the head of a horse.

To change the adjustment of the throat latch, the ring 6 is turned up and away from 75 the gag strap *v*, thereby withdrawing the studs 8 from the holes with which they engage in the gag strap *v*. The plate 4 can then be slid freely up or down on the gag strap to the desired position and fastened in 80 place thereon by turning the ring 6 down and thereby engaging the studs 8 with the opposite pair of holes.

The shank of the hook 3 is formed, as 85 shown in Fig. 1, with an opening, and the hook is so shaped that in order to engage it with or remove it from the eye *y*, the shank has to be turned up into a position transverse to the plane of the gag runner. Accidental disengagement of the hook from the 90 eye is thus prevented without using a spring or other retaining means.

All the metal fittings of the bridle, such as the rings *d* and *g*, the hooks *t* and *u*, the gag runners *w*, the hook 3 and the ring 6, having 95 bars on which leather straps are looped and fastened as shown in Fig. 5, are formed at the ends of such cross bars with guards 9, which lie close to the opposite edges of the straps, and between said guards with anti-friction tongues 10, which lie between the folds of the strap ends. The guards 9 prevent the straps from slipping lengthwise of the bars around which they are looped, and the tongues 10 prevent them from turning 100 thereon. Friction and wear between the leather and metal are thus avoided, and the life of the bridle is materially prolonged.

All billets or loose strap ends and leather or other loops are eliminated in the construction of the bridle, thereby effecting a 110 material saving of leather and improving the appearance of the bridle.

With the exception of one section or end of the gag strap *v*, and the buckle or fastening for adjustably connecting the throat latch therewith, perforation and weakening of the leather for the fastening and adjustment of buckles having tongues, according to the usual practice in making harness, 115 are also avoided, thereby further increasing the strength and durability of the bridle.

The chains *j*, besides providing for the adjustment of the length of the bridle, afford means for the adjustment of the length 120 of the check *s*, the hooks *u* being engaged for this purpose with any of the links of the chains between the cheek straps *a* and the hooks *l*. The hooks *t* of the reins may also be connected with any of the links of the 125 130

chains above the hooks *l*, to relieve horses having sore or tender mouths from more or less of the pull on the reins.

Various changes in minor details of construction and arrangement of parts may be made without departing from the principle and scope of the invention as defined in the following claims.

I claim:

10 1. In a bridle the combination of cheek straps, chains connected with said straps, and a bit having cheek pieces provided with means for adjustably fastening the bit to said chains and with guideways forming 15 keepers for confining the surplus portions of the chains in place.

2. In a bridle the combination of cheek straps provided with metal rings at their lower ends, chains connected at one end with 20 said rings and provided at the other end with links having stop projections, and a bit provided with cheek pieces having on the upper sides hooks with which links of the chains are detachably engaged to vary the 25 length of the bridle and formed with guideways for the chains below the hooks, the upper ends of the guideways being restricted to engage with the stop projections on the chains and prevent their withdrawal upward from the cheek pieces.

3. In a bridle the combination of cheek straps, chains connected at their upper ends with the lower ends of said straps and having stop projections at their lower ends, and 35 a bit provided at the ends with cheek pieces having hooks on their upper sides for adjustable connection of the chains with the bit and formed with a series of openings for adjustable attachment of reins and below 40 the hooks with guideways for the chains, the upper ends of the guideways being restricted to prevent the withdrawal of the chains upwardly from the cheek pieces.

4. In a bridle the combination with the 45 crown strap, of a gag strap attached to the crown strap, gag runners attached to the ends of the gag strap, and provided one with an eye and the other with a loop, and a throat latch provided at one end with a 50 hook, passing loosely through the loop of one gag runner, and adjustably connected at

the other end above the gag runner with the gag strap.

5. In a bridle the combination with the crown strap, of a gag strap attached to the 55 crown strap thereof and provided at the ends with gag runners one of which is formed with an eye and the other with a loop, said gag strap being formed adjacent to one end with two rows of holes, a throat 60 latch passing through said loop and provided at one end with a hook for detachable engagement with the eye, and a fastening adjustably connecting the other end of the throat latch with the gag strap and comprising a plate having ears on opposite sides between which the gag strap is guided and a ring having a cross bar around which the end of the throat latch is looped and fastened and another cross member pivoted to 65 said plate between its ears and provided with studs adapted to enter opposite holes in the gag strap when the ring is turned down.

6. In a bridle the combination with the 75 cheek straps, of chains connected at their upper ends with the lower ends of the cheek straps, a bit having cheek pieces formed on the upper sides with outwardly and downwardly bent forked hooks to engage opposite links of the chains and below the hooks with guides for the chains, and dogs pivoted in the forked ends of the hooks and adapted to turn inwardly and downwardly against the cheek pieces for holding the 85 chains on the hooks.

7. In a bridle the combination with the cheek straps, of chains connected at their upper ends with the lower ends of said straps, a bit having cheek pieces provided 90 with outwardly and downwardly projecting hooks for engagement with opposite links of the chains and with keepers below the hooks for confining the surplus portions of the chains in place, and means for locking the 95 chains in engagement with said hooks.

In witness whereof I hereto affix my signature in presence of two witnesses.

JAMES M. WALSH.
